UNITED STATES PATENT OFFICE.

JOHN SCHADE, OF HOLYOKE, MASSACHUSETTS, ASSIGNOR TO NATIONAL BLANK BOOK COMPANY, OF HOLYOKE, MASSACHUSETTS, A VOLUNTARY TRUST ASSOCIATION OF COPARTNERSHIP, HAVING AS TRUSTEES E. B. TOWNE, E. S. TOWNE, J. M. TOWNE, AND F. W. WILSON.

BOOK COVER.

Application filed July 28, 1923. Serial No. 654,299.

To all whom it may concern:

Be it known that I, JOHN SCHADE, a citizen of the United States, residing at the city of Holyoke, in the county of Hampden and

5 State of Massachusetts, have invented certain new and useful Improvements in Book Covers; and I do declare the following to be a full, clear, and exact description of the invention, such as will enable others 10 skilled in the art to which it appertains to make and use the same.

This invention relates to book covers, but more particularly has reference to articles of this description that comprise a back 15 portion to which is secured a ring carrying structure, and flexible covers hinged to said back portion, this style of device being commonly known as a "ring binder."

The particular object of the invention is 20 to so construct the metal back plate that it will not only provide complementary hinge portions but will also firmly secure to the back of said plate a facing of any suitable non-metallic material such as leather, fabric 25 and some kinds of paper.

In the accompanying drawing—

Figure 1 is a plan view of the inside of 30 the completed book cover with the covers opened—

Figures 2 and 3 are sections respectively 35 at the lines 2—2 and 3—3 of Figure 1, and Figure 4 is a detail sectioned perspective of the completed back portion.

Similar numerals of reference denote like 40 parts in the several figures of the drawing.

1 is any suitable non-metallic back and 2 is a metal plate superimposed thereon. At the side edges of this plate are integral spaced fingers 3 which are bent and formed 45 into projecting spaced alined eyes 4, the extremities of the fingers being clenched at 5 into the outside face of the back 1 near the edges thereof, so that it will be clear that the plate will not only stiffen the back and keep it from being distorted or wrinkled, but will also serve as the sole means for securely binding the back and plate together.

At suitable locations the plate is pierced to accommodate eyelets 6 (only one shown) which rise from the plate and to which 50 the usual ring structure is secured.

The bottom face of the plate is countersunk as at 7 to accommodate the head of the eyelet.

8 are the covers which are flexible and 55 preferably made of leather or any suitable non-metallic penetrable material, and at the inner edges of these covers are projecting spaced alined metal eyes 9 formed from a strip of metal having staggered spaced fingers 10 extending from opposite sides, one set of fingers being clenched to one face of a cover while the other set is bent and formed into the eyes 9 and has its extremities clenched into the other face of such cover. 60

The eyes 4 and 9 are then interengaged and pintles 11 inserted therethrough to complete the hinging.

No claim is made to the metal strip attached to the covers, but the manner of 70 forming the completed back portion affords a very economical and durable structure that is peculiarly adapted to the hinge elements carried by the covers.

What is claimed is:

The herein-described improvement in book 75 covers, which consists of a back portion of non-metallic penetrable material, a metal plate superimposed upon the inner face of said portion said plate having integral therewith along its side edges a series of fingers that are bent and formed into space alined projecting eyes, the extremities of said fingers being clenched into the outer face of said back portion, flexible covers having 80 secured along their inner edges a series of alined and spaced projecting eyes, the eyes of the back portion and covers being interengaged, and pintles inserted through said 85 eyes.

In testimony whereof I affix my signature hereto.

JOHN SCHADE.
